ROTARY HYDRAULIC ACTUATOR COMPRISING A ONE-PIECE UNITARY BODY AND MOUNTING END PORTION

Alfred G. French, Williamsville, N.Y., assignor to Houdaille Industries, Inc., Buffalo, N.Y., a corporation of Michigan

Filed Oct. 22, 1962, Ser. No. 231,986
4 Claims. (Cl. 92—121)

The present invention relates to improvements in rotary hydraulic actuators and more particularly concerns new and improved housing construction for hydraulic rotary actuators.

Heretofore, hydraulic rotary actuators have been constructed with housings consisting of a ring shaped body and separate end members attached to the body and defining therewith a hydraulic operating chamber within which the customary abutment and wing shaft vane structure are located for hydraulic actuation of the wing shaft which is attached to the component of associated apparatus to be motivated by the actuator. In such prior rotary actuators, the end which is mounted on or attached to the mounting structure of the associated apparatus or equipment and the actuator body tend to move relatively due to the many sudden reversals in rotation and the resultant torque strains to which the device is subjected in use. Although double vane actuators are liable to such undesirable relative movement of the housing and end member, single vane actuators are particularly liable to such relative movement due to the internal hydraulic unbalance existing in the operation of this type of actuator.

An important object of the present invention is to provide a new and improved rotary hydraulic actuator provided with a housing which is particularly applicable for uses where sudden reversals in rotation tend to cause movement between assembled housing parts.

Another object of the invention is to provide a novel hydraulic rotary actuator including a housing of the end or face mount type wherein the mounting end and body are constructed in one integral piece so as to avoid any possibility of relative movement or displacement of the body and end portions.

A further object of the invention is to provide a new and improved rotary actuator having a housing especially suitable for single vane actuators which have an internal hydraulic unbalance and thus are particularly susceptible to shifting between the ends and body of the housing.

Still another object of the invention is to provide substantial improvements in hydraulic rotary actuators adapted for heavy duty usage.

It is also an object of the invention to reduce the number of parts required for rotary actuators and thus substantially lowering the production costs and inventory of parts.

A yet further object of the invention is to provide a new and improved hydraulic rotary actuator having a housing construction which avoids the need for special mounting plates or adapters.

Other objects, features and advantages of the present invention will be readily apparent from the following detailed description of a preferred exemplary embodiment thereof taken in conjunction with the accompanying drawings, in which:

FIGURE 1 is an end elevational sectional view of a rotary hydraulic actuator embodying features of the invention, taken substantially on the line I—I of FIGURE 3;

FIGURE 2 is a fragmentary sectional detail view taken substantially on the line II—II of FIGURE 1;

FIGURE 3 is a longitudinal sectional detail view taken substantially on the line III—III of FIGURE 1; and

2

FIGURE 4 is an enlarged fragmentary sectional detail view of the encircled portion IV of FIGURE 3.

Hydraulic rotary actuators of the type illustrated are useful in the operation of equipment such as earth moving machinery, heavy duty steering apparatus, and other uses where oscillatory rotary driving force is utilized. It includes a wing shaft 5 having a radial wing or vane 7 oscillatable between opposite sides of an abutment 8 within a working chamber 9 in a housing 10. Hydraulic fluid for actuating the wing shaft 5 through oscillations of the vane 7 is introduced at opposite sides of the abutment 8 selectively, and alternatively exhausted, through suitable hydraulic passages 11 which are adapted to be connected in the usual manner to an operating hydraulic system of the equipment with which the actuator is associated.

According to the present invention, the actuator housing 10 comprises just two principal components, namely, a combined body and face mount end member 12 and a closure cap end member 13. To this end, the member 12 comprises a generally cup-shaped casting having an end face portion 14 and at least internally cylindrical body flange 15 defining the operating chamber 9 within the cavity of the member. In addition, the member 12 includes means, herein in the form of a pair of mounting flange ears 17 attached integrally in one piece to the end face portion 14 through an endwise base projection 18 and adapted to be secured through the medium of screws or bolts to a supporting structure 20 (FIGURE 3) of apparatus with which the actuator is associated in service.

For operative attachment to that movable part of the associated equipment to be motivated, an end portion of the wing shaft 5 projects externally of the end portion 14 of the housing and through a clearance aperture 21 in the mounting structure 20 and a registering clearance recess 22 in the mounting base 18. To journal the projecting end portion, an elongated hub 23 is provided on the end portion 14 with a suitable bearing 24 mounted therein and engaging the wing shaft. Between the bearing and the outer extremity of the hub 23 a hydraulic sealing ring 25 sealingly encircles the wing shaft and is mounted in a sealing ring groove 27 of substantial width, thereby assuring satisfactory protection against leakage past the wing shaft.

It will be observed that this is the only seal that need be provided at the mounting end of the housing 10 since the end portion 14 and the body flange portion 15 are of unitized construction. Furthermore, the elongated journal for the wing shaft 5 provided by the hub 23 assures maximum resistance to eccentric or bending strains that may be imposed on the wing shaft 5.

Means are provided for securing the end cap member 13 to the housing flange 15 in a manner substantially to preclude transverse relative displacement. For this purpose, a flange and groove joint is provided wherein the open end of the housing body flange 15 has a rabbet 28 within which an axially projecting annular complementary marginal flange 29 on the cap member 13 is firmly seated and maintained by means of screws 30 and dowels 31. A hydraulic seal, suitably comprising an O-ring 32, in the joint between the cap member and the engaged end of the housing flange 15, preferably operatively engaging within the reentrant angle formed by the cap flange 29, seals this joint against leakage of hydraulic fluid from within the working chamber 9.

Although for some purposes it may not be necessary to journal the wing shaft 5 in the cap member 13, so that the end cap will serve merely as an end thrust bearing for the wing head of the wing shaft, a desirable journalled relationship for a journal portion 33 of the wing shaft may be provided by a central hollow hub 34 on the end member carrying a suitable bearing 35 encircling the wing shaft portion 33. Sealing means such as an O-ring seal 37 are suitably provided at the inner end of the journal bore

through the hub 34 and engaging the adjacent shoulder end of the wing shaft head.

Anchorage of the abutment 8 within the working chamber 9 is suitably effected by means of dowels 38. In especially sturdy construction, the dowels 38 extend longitudinally entirely through the abutment 8 and at one end into sockets 39 provided therefor in the inner face of the end cap 13 and at the other end into aligned sockets 40 provided in the confronting working chamber face of the housing end portion 14. Through this arrangement, not only is the abutment 8 thoroughly retained against displacement under the hydraulic pressures developed in the working chamber 9, but the connecting dowels 38 supplement the attachment bolts 30 and the dowels 31 in retaining the cap 13 against any tendencies toward torque displacement in service.

Although the illustrated example of hydraulic rotary actuator has only a single actuating vane and abutment arrangement, it will be readily apparent that the same principles of construction insofar as the housing structure is concerned are applicable to a multi-vane arrangement.

It will be clear that the single piece unitary construction of the body and face mounting end of the housing member 12 preclude any possibility of relative displacement of these portions of the housing. Since the mounting lug ears 17 are integrally in one unitized piece with the housing member 12, there is no possibility of relative displacement of these parts of the housing with respect to other parts of the housing member 12. Thus, actuator life is increased as compared to housings having separate body and mounting face members, since misalignment of parts is substantially eliminated. Another advantage resides in that the need for a seal between the body portion and the mounting end portion of the housing member 12 is entirely eliminated since they are in integral one piece relationship. No fasteners are required between the mounting end portion 14 and the housing portion 15. Because of the unitized construction, production costs and inventory are substantially reduced. Further, since the body portion 15 and the mounting end member 14 and its hub 23 are all unitized, substantial mutual resistance to bending strains on the bearing 24 are afforded by the housing portion 15, and in addition by the end cap member 13 which is held positively against any transverse displacement and is quite thoroughly secured against torque displacements.

It will be understood that modifications and variations may be effected without departing from the scope of the novel concepts of the present invention.

I claim as my invention:

1. In a rotary hydraulic actuator including a wing shaft and a housing having means therein for hydraulically actuating the wing shaft oscillatably, said housing comprising:

a generally cup-shaped one-piece unitary body and mounting end portion defining a working chamber with an open end opposite said end portion, a closure cap secured over the open end of the body, said end portion having a unitary base for engagement with a supporting structure of equipment with which the actuator is associated, said base having a central axially opening recess affording clearance about a projecting end portion of the wing shaft and adapted to register with a clearance opening in said supporting structure.

2. In a rotary hydraulic actuator including a wing shaft and a housing having means therein for hydraulically actuating the wing shaft oscillatably, said housing comprising:

a generally cup-shaped one-piece unitary body and mounting end portion defining therein a hydraulic working chamber having an open end,

and a closure cap member secured to the open end of the body;

an abutment member in said chamber, and dowel pins extending entirely through the abutment and secured at their opposite ends into blind end sockets provided in alignment in the opposing faces of the end portion and said closure cap member.

3. In a rotary hydraulic actuator including a wing shaft and a housing having means therein for hydraulically actuating the wing shaft oscillatably, said housing comprising:

a generally cup-shaped one-piece unitary body and mounting end portion,

said end portion having means for journalling a projecting portion of the wing shaft therethrough for attachment to apparatus to be motivated by the actuator,

said unitary body having an open end opposite said end portion, a closure cap member secured to the open end of the body,

and an elongated hub and base projection on said end portion through which the wing shaft is journalled, said projection having a substantial clearance recess about said projecting portion of the wing shaft and opening axially for registration with a clearance opening in a supporting member.

4. In a rotary hydraulic actuator including a wing shaft and a housing having means therein for hydraulically actuating the wing shaft oscillatably, said housing comprising:

a generally cup-shaped one-piece unitary body and mounting end portion defining therein a hydraulic working chamber open at one end and having means on said body at said one end for attachment of a closure member,

a closure cap member secured to the open one end, an abutment member in said chamber, a plurality of dowel pins extending entirely through the abutment member and secured at their opposite ends into blind end sockets provided in alignment in the opposing faces of the end portion and said closure cap member,

said end portion having means for journaling a projecting portion of the wing shaft therethrough for attachment to apparatus to be motivated by the actuator,

an elongated hub and base projection on said end portion through which the wing shaft is journalled, an attachment ear flange means laterally integrally extending from the extremity of said base projection, and

said base projection having a substantial clearance recess about said projecting portion of the wing shaft and opening axially for registration with a clearance opening in a supporting member.
